CLAIM

The ornamental design for an operating-mode selecting assembly of a reader unit, selector, and key, as shown and described.

DESCRIPTION

FIG. 1 is a perspective view of an operating-mode selecting assembly of reader unit, selector, and key showing our new design;

FIG. 2 is an enlarged front view thereof;

FIG. 3 is an enlarged rear view thereof;

FIG. 4 is a right side view thereof;

FIG. 5 is a left side view thereof;

FIG. 6 is an enlarged top view thereof; and,

FIG. 7 is an enlarged bottom view thereof.

The broken lines in the figures are for the purpose of illustrating portions of the operating-mode selecting assembly of reader unit, selector, and key that form no part of the claimed design.
